J. B. DALBEY.
FUEL AND SPARK CONTROLLING MECHANISM.
APPLICATION FILED MAY 18, 1915.

1,209,941.

Patented Dec. 26, 1916.

UNITED STATES PATENT OFFICE.

JOEL BENJ. DALBEY, OF NEVADA, IOWA, ASSIGNOR OF ONE-HALF TO JAY A. KING, OF NEVADA, IOWA.

FUEL AND SPARK CONTROLLING MECHANISM.

1,209,941.

Specification of Letters Patent. Patented Dec. 26, 1916.

Application filed May 18, 1915. Serial No. 28,965.

To all whom it may concern:

Be it known that I, JOEL BENJ. DALBEY, a citizen of the United States, and resident of Nevada, in the county of Story and State of Iowa, have invented a certain new and useful Fuel and Spark Controlling Mechanism, of which the following is a specification.

The object of my invention is to provide a fuel and spark controlling mechanism of simple, durable and inexpensive construction.

A further object is to provide in such a device mechanism for controlling the flow or ignition of fuel to a generator, which mechanism is also adapted to control the flow of fuel to the burner.

Still a further object is to provide such a device, the mechanism of which is adapted to operate contact points by closing an electric circuit.

Still a further object is to provide a device of the class mentioned, comprising a single installation in convenient form for controlling generating fuel and burning fuel for one or for a plurality of lamps, and for controlling contact points adapted to be in an electric circuit employed for causing a spark for igniting the generating fluid.

My invention consists in the construction, arrangement and combination of the various parts of the device whereby the objects contemplated are attained as hereinafter more fully set forth pointed out in my claims and illustrated in the accompanying drawings, in which:

Figure 1 shows a side elevation partly in section of a fuel and spark controlling mechanism embodying my invention. Fig. 2 shows a horizontal sectional view taken on the line 2—2 of Fig. 1, one of the valves being shown in section taken on a lower plane than that of the main portion of the view. Fig. 3 shows a vertical sectional view taken on the line 3—3 of Fig. 2, and Fig. 4 shows a front elevation of the device as installed on a wall or other support.

My improved fuel and spark controlling mechanism is designed to be used in connection with a lamp or lamps in a system, such for instance, as that shown in my application for Patent Number 14,830, filed March 16, 1915. I have, however, in my present drawings, shown only the apparatus or installation adapted to be mounted on a wall

or other support, and designed for controlling fuel, and the contact points forming part of an electric circuit, which circuit is employed for producing a spark for igniting the fuel for generating gas.

In the exemplification of my present invention, illustrated in the drawings filed herewith, I have employed the reference numeral 10 to indicate generally the upright member of a frame. At the upper and lower ends of the member 10 are forwardly extending frame members 11. At the forward portion of the frame 10 is a plate 12 secured to the members 11 and adapted to fit against the wall or other support.

The members 11 are provided with extensions 13 adapted to be secured to a support by means of screws 14. The plate 12 may be detachably mounted on the frame by means of similar screws 14.

Suitably supported on the frame is an upright tube or pipe 15, having at its lower end a rearward extension 16. On the interior of the extension 16 is a contracted portion 17 having a small central opening 18. The wall of the portion 17 around the opening 18 is inclined from its central portion outwardly and forwardly toward the tube 15 for a purpose which will be hereinafter referred to.

A supply tank 19 is suitably located and is adapted to contain generating fuel. A tube 20 communicates with the supply tank 19 and with the extension 16. The tank 19 may be arranged above the level of the upper end of the tube 15, or may be partially filled with air under pressure.

Communicating with the tube 15, by means of a tube 21, is an air pressure tank 22 closed except for its communication at its lower end with the tube 21. It will be seen that the pressure of the fuel or air in the tank 19 will tend to compress the air in the tank 22.

Screwed into the wall of the tube 15 in line with the opening 18 is a rod 23 on which is a head 24 outside the tube 15. The rod 23 extends into the extension 16 and is provided with a reduced tip or end 25 so arranged that when the rod 23 is screwed inwardly the tip 25 will enter the opening 18 for cleaning it.

Above the extension 16 the tube 15 is provided with a plurality of extensions 26.

Communicating with the various extensions 26 are fuel carrying tubes 27, designed to lead to a plurality of lamps for carrying generating fuel thereto.

5 Suitably mounted on the frame is a main fuel supply tube 28, having a plurality of extensions 29 which preferably lie in a vertical plane parallel with the plane in which the extensions 26 are located. Communicating with the various extensions 29 are fuel supply tubes 30 designed to lead to a plurality of lamps.

15 Slidably mounted in the plate 12 and the frame between the respective extensions 26 and the respective extensions 29, are a plurality of sliding or push rods 31, preferably arranged in vertical series. On the rods 31 outside the plate 12 are suitable heads 32. Each rod 31 is formed with two spaced 20 notches 33, adapted to be entered by a spring 34 mounted on the frame.

25 In each of the extensions 26 and 29 is a valve 35 having a stem 36 projecting in a horizontal plane toward the vertical plane in which the rods 31 lie. On the ends of 30 the stems 36 are upright extensions 37, normally held in upright position by springs 38.

30 On each rod 31 is a finger 39 extending laterally from the rod and having at its outer end a rearward extension 40. On each rod 31 forwardly of the finger 39 is a laterally extending finger 41, having at its outer end a forward extension 42. The extension 42 is of spring metal and has at its forward end a downwardly curved portion 43.

45 Suitably mounted on the frame adjacent to the portions 43 are contact points 44 adapted to be engaged by the portions 43 in one position of the movement of the rods 31. It will be understood that the portions 43 are of suitable conducting material and that said portions 43 form contact points, and that in the lighting system, of 50 which my present device is designed to form a part, the portions 43 and the contact points 44 are designed to be included within an electric circuit having gaps at proper points adjacent to the lamps for causing a spark when the circuit is closed by the contact of 55 the members 43, and the points 44 for lighting generating fluid or lighting lamps after generating.

55 The operation of my device will now be described.

60 It will be understood that my improved device, as herein described, is designed to be installed in connection with a lamp or lamps as part of the lighting system, which 65 system should include a suitable tank for supplying fuel to the tube 28 and an electric circuit as above mentioned. When thus installed the operation of my device is as follows: The rods 31 are designed to ordinarily stand in position with the end of the

70 spring 34 received in the forward notch 33. This is the middle and neutral position of the rods, and is the position illustrated by the second from the top and the lowermost rods shown in Fig. 1. When it is desired to light one of the lamps, the rod 31 adjacent to the extensions 26 and 29 connected with the lamp in question are first pushed inwardly to the position shown by the upper rod 31 in Fig. 1. When in such position 75 the finger 41 will engage the extension 37 of the stem valve in the extension 26, adjacent to the rod 31 moving it rearwardly against the pressure of the spring 38, for opening said valve and allowing the pressure of the air in the tank 22 to force the generating fluid through the tube 27 to the proper lamp for generating purposes. In this connection it will be noted that the pressure of the air in the tank 22 acts automatically on the alcohol or other generating fluid. The spring 38 on the stem of the valve tends to return the rod 31 to its closed position. The size of the opening 18 is so small that while the head 32 is held at its inner limit of movement very little fuel is supplied to the tube 15, so that there is little danger of an overflow of generating fluid being forced to the lamp for generating the main fuel supply tube. When the rod has 95 been held at its inner limit of movement for a proper time for supplying generating fluid to the lamp, it is then pulled out to its outer limit of movement, as illustrated by the third rod from the top in Fig. 1, to position 100 with the spring 34 received in the inner notch 33. During the outward movement, the points 43 and 44 contact for closing the electric circuit, and causing a spark for generating the alcohol or other fluid. The outward movement of the rod 31 causes the finger 39 to engage the extension 37 of the valve in the adjacent extension 29 swinging it forwardly as illustrated by dotted lines in Fig. 3 for turning on the gasoline or other fuel supply.

105 It will be noted that the upper end of the extension 37 stands below the member 40, as shown by said dotted lines, when the rod 31 is at its outer limit of movement, so that the spring 38 will not move the rod 31 inwardly. The rod 31 is left pulled out as long as it is desired to keep the lamp lighted.

110 When the rod is at its outer limit of movement, the member 43 stands clear of the contact point 44, as illustrated by the member 43 on the third rod 31 from the top in Fig. 1.

115 The operation just described may be repeated for each of the lamps included in the installation.

120 It will be noted that the members 17 are so constructed that they are inclined rearwardly in the extensions 26, so that foreign matter or sediment in the alcohol or other generating fluid will not tend to collect im- 125

mediately in the opening 18, but will drop downwardly to the bottom of the extension 16 and around the inclined portions of the members 17. If, however, during the use 5 of my device, the opening 18 should become clogged at any time, the heads 32 may be unscrewed from the rods 31 and the plate 12 removed, whereupon the rod 23 may be screwed inwardly for causing the portion 25

10 thereof to enter and clean the openings 18.

It will be understood that in my drawings, I have simply illustrated one form of my invention and that many modifications thereof may be made, and it is my intention 15 to cover by this application any such changes which may be included within the scope of my claims.

It will also be understood that my device may be used for lamps, stoves, burner 20 or other purposes.

I claim as my invention—

1. In a device of the class described, a fixture comprising a frame, a pair of fuel supply tubes thereon, and spring controlled 25 valves in said tubes, a movable member mounted on said frame and adapted in different positions of its movement to selectively operate the valves in said tubes against the action of their spring elements, 30 means for holding said movable member in either of its valve operating positions, a contact point on said frame, and a contact point carried by said movable member and adapted to engage said first contact point when 35 said member is in a position intermediate of its valve controlling position.

2. In a device of the class described, a fixture comprising a frame, a pair of tubes thereon, spring controlled valves in said 40 tubes, a movable member mounted on said frame and adapted in different positions of its movement to selectively operate the valves in said tubes against their spring elements, a fuel supply tank located above the 45 upper end of one of said tubes, means for carrying fuel from said tank to one of said tubes, and an air tank communicating with the upper end of said last mentioned tube.

3. In a device of the class described, a fixture, comprising a frame, a manually movable member mounted thereon, and suitable 50

supply tubes, valves for controlling the flow of fuel from said tubes, arms projecting from said movable member, said valves having stems projecting into the paths of said 55 arms, whereby when the movable member is moved to one position one of said valves is open, and when the movable member is moved to another position another of said valves is open.

4. In a device of the class described, a support, a tube mounted thereon, a valve for controlling the discharge of fluid from said tube, a tank, a tube leading from said tank to said first tube, a comparatively small passage 65 for admitting fuel from said second tube to said first tube, an air tank communicating at its lower end with said first tube, means for yieldingly holding said valve in closed position, and movable means for moving said valve to open position.

5. In a device of the class described, a support, a tube mounted thereon, a valve for controlling the discharge of fluid from said tube, a tank, a tube leading from said 75 first tube, a comparatively small passage for admitting fuel from said second tube to said first tube, an air tank communicating with said first tube, a movable member for operating said valve, and a cleaning device capable of being operated from outside of said tubes, and adapted to be moved into and out of said contracted passage for cleaning the same.

6. In a device of the class described, a fixture comprising a frame, a manually movable member mounted thereon, and suitable supply tubes, valves for controlling the flow of fuel from said tubes, arms projecting from said movable member, said valves having stems projecting into the paths of said 85 arms, whereby when the movable member is moved to one position one of said valves is open, and when the movable member is moved to another position another of said 90 valves is open, and means for yieldably holding said valves in closed position.

Des Moines, Iowa, April 30, 1915.
JOEL BENJ. DALBEY.
